UNITED STATES PATENT OFFICE.

JOHN THOMAS HAILWOOD, OF ROCHDALE, ENGLAND.

STOP-COCK OR TAP.

SPECIFICATION forming part of Letters Patent No. 502,094, dated July 25, 1893.

Application filed November 1, 1892. Serial No. 450,662. (No model.)

To all whom it may concern:

Be it known that I, JOHN THOMAS HAILWOOD, a subject of the Queen of England, residing at Rochdale, in the county of Lancashire, England, have invented certain new and useful Improvements in Stop-Cocks or Taps, of which the following is a specification.

My invention has relation to stop-cocks or taps; and it relates more particularly to that class provided with plugs and in which the part to which a key or wrench is applied is formed upon the smaller projecting end of the same.

The principal objects of my invention are first, to provide a plug, stop-cock or tap in which the construction is simplified and the arrangement of the parts thereof are lessened so as to render the same less expensive and much more durable and effective in action; second, to provide a stop-cock or tap with a hollow tapering plug having the smaller end projecting beyond the body or casing of the device and with a set-screw for adjusting the spindle or plug carrier to position; and third, to provide a stop-cock or tap provided with a hollow tapering plug whose smaller square, hexagonal or other shaped end projects beyond the casing and adapted to receive a key or wrench.

My invention consists of a stop-cock or tap provided with a hollow plug and carrier therefor, constructed and arranged so as to permit of the adjustment of the hollow plug to its internal tapering seat and with a certain portion thereof externally adapted to receive a key or wrench.

My invention further consists of a stop-cock or tap provided with a hollow plug and spindle therefor, and a set-screw for adjusting the spindle or carrier of the hollow tapering plug to its internal seat in the device and having the smaller end projecting beyond the body or casing of the device, whereby the projecting smaller end of said hollow plug is made available for the reception of a key, wrench or similar appliance.

My invention further consists of a hollow plug stop-cock or tap having a thimble or hat shaped piece with perforations therein and operating upon the larger end of the plug in conjunction with a spindle provided with a

head abutting a detachable cap and an adjusting-screw; and my invention further consists of the improvements in hollow plug stop-cocks or taps hereinafter described and 55 claimed.

The nature, scope and characteristic features of my invention will be more fully understood from the following description taken in connection with the accompanying drawings forming part hereof; and in which—

Figure 1, is a longitudinal central section of a stop-cock or tap embodying features of my invention and showing an exterior casing having a tapering seat integral therewith, a 65 tapering plug having an axial and radial fluid-way, an unyielding plug carrier adapted to afford access to the axial portion of the fluid-way and engaging the top of the cavity in the plug, and a set-screw for co-operating with 70 the plug carrier. Fig. 2, is a cross-section of the same; and Fig. 3, is a longitudinal central section, showing a plug carrier engaging the lower rim of the plug.

In the drawings A, is the exterior casing of 75 the tap or cock provided with an integral tapering seat a' , for the reception of a tapered plug B, whose smaller extremity projects beyond the exterior casing A, and is provided with a rectangular seat b , for the reception of 80 a wrench or key. The plug B, is provided with an axial and a radial fluid-way that co-operate with suitable inlet and outlet openings in the exterior casing A, so that the liquid or other substance may flow through the tap 85 or cock when the latter is in open position in the manner indicated by the arrows in the drawings.

C, is a cap for closing an aperture in the exterior casing A, and is adapted to afford 90 means for permitting of the introduction or withdrawal of the plug B. It is important that the plug B, should be held firmly and snugly to place upon its seat a' , at all times, in order to avoid leakage and insure the 95 proper operation of the tap or cock, while at the same time the lower portion of the plug, i. e. the axial fluid-way, must be kept open. These results are accomplished according to my invention by the employment of a set-screw and its complemental unyielding plug-carrier, which is constructed in such manner 100

that it does not close the axial fluid-way. Of course the unyielding plug-carrier may assume various forms.

Referring to Figs. 1, 2 and 3, the plug carrier E is provided at its lower extremity with an enlargement or head e, fitting snugly in a recess e, in the cap C.

D, is a set-screw working in a suitably tapped aperture in the cap C.

10 Between the head e, of the plug-carrier, and the flat end of the set-screw D, is a layer or packing F, of asbestos or other suitable material. When the set-screw D, is turned the plug-carrier E, is shifted in the direction of 15 its length, and this movement of the plug carrier is availed of for adjusting the plug B, to its seat a'. In Figs. 1 and 2, the upper extremity of the plug-carrier E, comprises a small stem e², that abuts upon the upper portion 20 of the recess in the plug B, and thus forms a pivot about which the plug B, may be turned. Moreover the axial fluid-way is fully open, because the fluid or other substance flows around the stem e², and is thus permitted 25 to pass through the axial fluid-way as is indicated by the arrows in Fig. 1.

In Fig. 3, the upper extremity of the plug carrier E, is provided with an annular flange e³, that constitutes a pivot upon which the 30 lower rim of the plug B is revolvably supported. In order to afford a passage for the fluid or other material through the axial fluid-way of the plug B, radial apertures h, are provided in the annular flange e³, so that the arrows in 35 said figure indicate the passage of the fluid or other material through the cock or tap.

b², is an oil-hole cut or otherwise formed in the smaller portion of the plug B, and through which oil may be supplied for lubricating the 40 plug and its complemental carrier E.

G, is a cap for closing the oil hole b².

From the foregoing description it appears that all of the devices illustrated in the accompanying drawings are provided with an 45 exterior casing A, having a tapered seat a', for the reception of a hollow plug B, and with an unyielding plug-carrier operated by a set-screw and constituting a pivot for revolvably supporting the plug B, in such manner that free 50 access to the interior thereof is afforded, and in such manner that the plug may be readily adjusted to its seat.

Having thus described the nature and objects of my invention, what I claim as new, 55 and desire to secure by Letters Patent, is—

1. A stop cock or tap, comprising a casing provided with an inlet and an outlet and an internal tapering seat, a hollow tapering plug provided with fluid-ways and having the smaller end extending vertically beyond the 60 casing and forming a seat for the reception of a key or wrench, a plug-carrier provided with a packed seat, a cap detachably engaging said casing and a vertical adjusting screw inserted through said cap and adapted to engage with 65 the seat of said plug-carrier, substantially as and for the purposes set forth.

2. A stop cock or tap, comprising a casing having an inlet and an outlet and an internal tapering seat, a hollow tapering plug with a 70 thimble or hat shaped internal body and fluid-ways co-operating with the inlet and outlet of said casing, a plug-carrier provided with a packed seat, a cap detachably engaging said casing and a vertical adjusting screw inserted 75 through said cap and adapted to engage with the seat of said plug-carrier, substantially as and for the purposes set forth.

3. A stop-cock or tap, comprising a casing provided with an inlet, an outlet and an internal seat, a hollow plug engaging with said seat, a carrier or spindle for said plug provided with an annular flange forming a pivot for revolvably supporting the plug to position, radial apertures in said flange for the passage 80 of fluid through the device, an oil hole provided in the smaller end of said plug and having a cap for closing the same, substantially as and for the purposes set forth.

4. A stop-cock or tap, comprising a casing 90 provided with an inlet, an outlet and an internal-seat, a plug having the smaller end projecting beyond the casing for the reception of a key or wrench and with axial and radial fluid-ways, a plug-carrier provided with a 95 flange having radial apertures therein and supporting one end of the plug and said carrier seated to or abutting against a set-screw for adjusting the same to position, a removable cap connected with said casing and detachably connected with said set screw, substantially as and for the purposes set forth.

In witness whereof I have hereunto set my signature in the presence of two subscribing witnesses.

JOHN THOMAS HAILWOOD.
